STOOL HOLDING ATTACHMENT FOR TABLES

Oliver A. Christianson and Floyd A. Naramore,
Seattle, Wash.

Application November 18, 1931, Serial No. 575,806

2 Claims. (Cl. 155—123)

Our invention relates to table attachments for supporting stools or chairs and the object of our invention is to provide simple and efficient means attachable to the under side of a table for suspending a stool or chair in an out of the way location underneath a table with the legs of the stool or chair clear of the floor.

In lunch rooms and like places where large numbers of stools or chairs are used for seating persons at table the stools or chairs are very much in the way when they are not in use. If the stools or chairs are pushed under the tables they still rest on the floor and are an obstruction which has to be moved in sweeping or cleaning the floor and they will often become unevenly distributed or bunched so that they will have to be redistributed before they are used. The stools or chairs are sometimes placed on the tables to clear the floor but when this is done the tables must be cleared of dishes and the like before the stools or chairs can be placed thereon and the stools or chairs must then be taken down before the tables can again be set or used and after the stools or chairs are taken down they may be in the way or may become bunched or unevenly distributed as respects the places at the table. Stools or chairs placed on tables also may damage the tables.

We overcome the objections above pointed out by providing simple and efficient means for supporting the stools or chairs in suspended or hanging position underneath the tables said stool or chair supporting means being cheap in construction, convenient to hang the stools or chairs on or remove the stools or chairs from, and out of the way at all times.

Other and more specific objects of our invention will be apparent from the following description taken in connection with the accompanying drawing.

In the drawing Fig. 1 is a cross section of a table having a stool or chair holding device constructed in accordance with our invention installed thereon, parts being shown in elevation.

Fig. 2 is a fragmentary side elevation of the same.

Fig. 3 is a fragmentary bottom plan view of said table.

Figs. 4, 5, and 6 are cross sectional views of tables having stool or chair holding devices of modified form installed thereon.

Fig. 7 is a fragmentary longitudinal section of a table showing still another modified form of stool or chair holding device.

Like reference numerals designate like parts throughout the several views.

Referring to Figs. 1 to 3, the numeral 10 designates a rectangular table of ordinary construction, which may be of any length. 11 designates a strip secured to the under side of said table in a plane at right angles to the table top and extending lengthwise of the table midway between the two sides thereof, one edge of the strip 11 being in engagement with the table top. 12 are stool or chair supports extending crosswise of the table and spaced below the table top, and secured as by bolt members 13, nuts 14 and plates 15 to the strip 11. The upper ends of the bolt members 13 may be bent outwardly and secured, as by screws 16, to the table top. The bolt members 13 together with the strip 11, secured to the table top in the manner shown and described form a strong and rigid construction which holds the stool or table supports 12 securely in place. 17 are hung on the supports 12 with the seat portions of the stools resting on said supports and the legs of the stools suspended well above the floor, as shown by dotted lines in the drawing.

In Fig. 4 we have shown a modified form of the invention in which angular bracket members 18 are used instead of the bolt members 13, said bracket members being secured to the table top and to the strip 11 and to the stool or chair supports 12, thus affording a very strong and substantial construction.

Fig. 5 shows still another modified form of construction in which stool supports 19 preferably formed of metal are secured directly to the under side of the table top and have horizontal portions 20 on which the stools or chairs may be supported.

The operation of the stool supports shown in Figs. 4 and 5 is same as the operation of the support shown in Figs. 1, 2 and 3.

In Fig. 6 we show a modified form of stool support in which a beam member 21 is secured to the under side of the table and extends lengthwise of the table and downwardly therefrom and hooks 22 are provided on the member 21 for engagement with rungs 23, or like parts of stools or chairs.

In Fig. 7 we show another modified form of stool or chair supporting means in the nature of brackets 24 arranged in pairs and having their lower edges extending toward each other whereby a stool may be inserted between the two brackets of each pair with the edges of the stool seat resting on the brackets. The lower edges of these

brackets may be of inverted T shape to receive stools on both sides of the bracket, as shown.

In the devices shown in Figs. 1 to 5 inclusive the stool or chair supports extend underneath the seat of the stool or chair between the legs thereof and support the stool or chair entirely beneath the table, with the legs of the stool or chair well above the floor in such a manner that the stool or chair is completely out of the way and permits the floor under the table to be swept or cleaned. The stools or chairs are quickly and easily placed on or taken off of the supports and are always properly distributed around the tables when the supports are used.

The operation of the stool or chair support shown in Fig. 7, is substantially the same as the operation of that shown in Figs. 1 to 5 except that the stool is supported from the edges thus allowing stools with center obstructions as rotatable seat mountings to be supported by this form of support.

The term stool used in the appended claims is intended to designate any stool or chair of this nature capable of being hung on supports of this type. The foregoing description and accompanying drawing clearly disclose a preferred embodiment of my invention, but it will be understood that this disclosure is merely illustrative and that such changes in the invention may be made as are fairly within the scope and spirit of the following claims.

We claim:

1. Stool supporting means for use beneath a table, embodying a relatively flat substantially horizontal stool supporting member extending crosswise of a table top in substantially parallel relation thereto and spaced a short distance therebelow, the ends of said stool supporting member terminating a short distance inwardly from the sides of said table top and mounting means securing said supporting member to said table top, said mounting means being positioned substantially midway between the two ends of the stool supporting member and substantially midway between the two sides of the table, the

distance between said mounting means and the respective ends of the stool supporting member being equal to more than one half the width of the stool to be supported on said stool supporting member.

2. The combination with a table of greater length than width, of stool supporting means pro-

viding underneath said table, embodying a bar used to designate any stool or chair of this nature capable of being hung on supports of this type. The stool supporting member extending crosswise of the top of said table midway between the two sides thereof, and a relatively flat substantially horizontal stool supporting member extending crosswise of the lower edge of said bar and secured to said bar, the stool supporting member being substantially equal in width to the width of the stool to be supported on said stool supporting member.
